[57] CLAIM

The ornamental design for a storage and display box for watch, as shown and described.

DESCRIPTION

FIG. 1 is a perspective view of a storage and display box for watch showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a right side elevational view thereof; the left side elevational view being a mirror image thereof;

FIG. 7 is a perspective view thereof with the cover removed and inverted in position to receive the box in its display mode; and,

FIG. 8 is a perspective view thereof with the box in its display mode.

The broken line showing of a watch is for illustrative purpose only and forms no part of the claim.
